UNITED STATES PATENT OFFICE.

WALTER W. CARSON, OF TIPTON, INDIANA; LIVINA PEARL CARSON, OF TIPTON, INDIANA, ADMINISTRATRIX OF SAID WALTER W. CARSON, DECEASED.

BACK-STOP ATTACHMENT FOR STRAW-STACKERS.

1,376,251.

Specification of Letters Patent. Patented Apr. 26, 1921.

Application filed August 30, 1918, Serial No. 252,038. Renewed March 17, 1921. Serial No. 453,067.

To all whom it may concern:

Be it known that I, WALTER W. CARSON, a citizen of the United States, residing at Tipton, in the county of Tipton and State of Indiana, have invented new and useful Improvements in Back-Stop Attachments for Straw-Stackers, of which the following is a specification.

The object of the invention is to provide means which may be readily carried by a straw stacker of the ordinary construction, which will control the delivery or stacking of straw as it leaves the spout or blower pipe so that a stack of comparatively uniform shape may be produced thereby, and properly topped out so as to be protected against the weather, to distinguish it from those stacks formed in the ordinary way and in which, while the side next to the stacker is comparatively abrupt and therefore will serve to turn the rain and other moisture, the side remote from the stacker is more or less straggling and spread-out, so that the straw is not properly protected. It is therefore fundamentally the object of the invention to provide means for restraining the straw as it is delivered from the spout, to confine the deposit thereof within certain limits and thus build a stack which is of relatively uniform shape throughout, without particular regard to its size, so that when topped out the main portion of the material contained in and forming the stack will be protected and thus preserved against rust, rotting and the like.

A further object of the invention is to provide an apparatus of the type and for the purpose indicated which can be readily folded and stored upon a stacker of the ordinary construction, so that the same may be readily transported with the stacker from place to place without inconvenience to the operator.

Further objects and advantages will appear in the following description of a preferred embodiment of the invention, it being understood that changes in form, proportion and details may be resorted to, within the scope of the appended claims, without departing from the spirit of the invention.

In the drawing:—

Figure 1 is a side view of a back stop or

restraining attachment arranged in the operative position as applied to a stacker, 55 the latter being shown merely in outline.

Fig. 2 is a plan view of the same.

Fig. 3 is a side view showing the back stop or restraining apparatus in folded position relative to the stacker as when being 60 transported.

Fig. 4 is a detail view of the back stop screen and means whereby the same is mounted upon and connected with the auxiliary boom or extensible element of the 65 supporting mechanism.

Fig. 5 is the vertical sectional view of the plane indicated by the line 5—5 of Fig. 1, showing the portions of the apparatus on the rear end of the stacker in elevation. 70

Figs. 6 and 7 are fragmentary views of details hereinafter explicitly referred to.

The apparatus embodying the invention is shown in connection with a thresher 10 of the ordinary type having a stacker spout 75 11 which is composed of telescoping sections 11^a, 11^b to provide for extension, with a flexible or angularly adjustable neck or elbow 12, a terminal hood or deflector 13, and a supporting bracket 14 which is pivotally mounted upon the frame of the threshing machine to permit of angular swinging movement in a horizontal plane so as to distribute the discharge of straw from the outlet of the spout. 85

Also carried by the frame or body of the threshing machine is a mast or post 16 adapted when in its operative position, to stand upright where it is held by the guy rope 17 and when folded to occupy a substantially horizontal position approximately parallel with the stacker spout which is foldable in the ordinary way by swinging it laterally around its pivotal point of mounting to extend forwardly along and above 95 the frame of the threshing machine. This mast or post is provided with a carrying shaft 18 mounted in bearings 19 supported by the frame of the threshing machine, and connected with said shaft is a crank arm 100 20 freely operating in a vertical guide 21 and having connected therewith an operating cable 22 reeled upon a drum 23, Fig. 6, to which is attached an operating crank 24. By means of this operating crank the mast 105 or post may be raised or lowered, the up-

ward movement thereof being limited, as will be understood, by the length of the guy rope 17, and to prevent accidental unwinding of the elevating rope or cable, a pawl and ratchet locking means 25 may be employed.

Carried by the mast or post is a screen supporting element or boom 26, the connection between said boom and mast being such as to provide for swinging movement of the former around the latter and also pivotal swinging movement in the plane of the latter. To this end a bracket 27 is mounted upon the mast or post to turn thereupon as an axis, while the end of the main boom is pivotally connected as at 27^a with said bracket to provide for vertical swinging movement as the height of the stack increases. It is desirable that this main supporting element or boom shall move approximately with the straw delivery spout and therefore the latter is provided with a hanger 28 having a runner consisting of a roller 28^a to traverse the boom. In this way the lateral swinging or distributing movement of the spout in the course of filling the stack is communicated to the boom of the apparatus so that the screen 29 which constitutes the back stop and is arranged within the path of the discharge from the spout is maintained at all times in the proper relative position. The connection between said screen (which essentially is of open work netting or the like to permit of the passage of air therethrough while serving as an obstacle for the straw) and the main supporting boom 26 includes an auxiliary or extension boom or element 30 fitted to slide in a sleeve 31 which is tiltably or pivotally mounted as at 32, upon the main beam and is held at the desired angular adjustment with reference to the main boom by an operating cable 33 attached to the end of said sleeve, passing around a direction pulley 34 and extending to a drum or windlass 35 having a pawl and ratchet locking means 36. By letting out or taking up this cable the angular adjustment of the tilting sleeve and hence of the extensible or auxiliary boom may be varied. Also the extensible boom is adjustable longitudinally in the sleeve by means of the coöperating cables 37 and 38, the former of which is attached to the outer end of the extension element and the latter to the inner end thereof, passing around the direction pulley 39, and both cables being properly secured at the other end to a double drum or windlass 40 which may as shown be mounted upon the main boom. Obviously by turning the windlass 40 in one direction the auxiliary boom will be extended whereas by turning said windlass in the opposite direction the said element will be drawn back and in this way it may be positioned as desired to locate

the screen or back stop at the desired distance from the discharge end of the straw spout.

The outlet of the spout and the screen may be located close to the ground when the building of a stack is commenced, and should be elevated gradually as the stack is formed, and in order to provide for this adjustment, a cable 41 is connected with the main boom at the outer or free end and after passing over a direction pulley 42 at the top of the mast or post is reeled upon a windlass 43 having a pawl and ratchet stop mechanism 44. After the proper angular adjustment of the boom to position the outlet of the spout, and screen at the desired elevation, the pawl and ratchet locking mechanism maintain said positions during the lateral swinging or distributing movement of the spout accompanied as above indicated by the screen which remains always in front of the outlet of the spout and in a position to prevent the scattering of the straw as it leaves the same. By gradually raising step by step the outlet end of the spout and the screen as the stack grows, a comparatively abrupt outer side may be provided for the stack, and finally the latter may be topped off, as desired to form a water shed to protect the straw within the body portion of the stack.

Also in order that the screen or back stop proper may be folded compactly with reference to the other parts of the apparatus, the stem 45 thereof is pivotally mounted as at 46 upon the extremity of the auxiliary boom and a brace 47 is connected with the projecting upper portion of said stem and is detachably anchored as by a pin 48 to the boom when the parts are arranged for operation. When the apparatus is to be folded said pin may be withdrawn and the screen folded into a plane substantially parallel with the main and auxiliary booms. It is the common practice to fold the delivery spout by swinging it around toward the front over the frame of the threshing machine, and by reason of the mountings above described the main boom and the features carried thereby including the auxiliary boom and screen may be correspondingly swung laterally as indicated in an intermediate position in Fig. 3 until they occupy a position above the body portion of the thresher when the boom elements may be seated in a holding bracket 49, Fig. 7, provided for their reception near the front of the machine and the mast or post may then be lowered as indicated in Fig. 3 by a reverse movement of the windlass 23. To extend the apparatus for use, obviously, the reverse of the above operation should be conducted, namely the mast or post should first be swung to its upright position by the manipulation of the wind-

lass 23, until checked by the guy rope 17, whereupon by operating the windlass 43 sufficiently to raise the spout and main boom with its attachments and clear the bracket 49, the same may be swung laterally to project rearwardly from the threshing machine. The spout and main boom may then be lowered so as to properly position the screen and the outlet of the spout and 10 as the straw is discharged the spout as usual is swung in the arc of a circle from side to side, the outlet thereof with the screen being raised from time to time as the stack increases in height. The position 15 of the screen with reference to the outlet of the spout will determine the shape of the side of the stack remote from the threshing machine, so that the same may be built up substantially perpendicularly from the 20 ground.

Also the diameter of the stack may be determined by the adjustment of the extensible element of the screen supporting means, consisting of said auxiliary boom 25 which may be tilted more or less to properly position the screen vertically with reference to the outlet of the spout, and as the stack increases in height the further extension of said element together with the 30 spout may be necessary in order to impart to the stack the desired shape and dimensions vertically as well as laterally.

Having described the invention I claim:

1. A back stop attachment for a stacker, 35 having a screen for restraining straw as it is discharged from the stacker spout, a pivotally mounted mast or post, a guy rope connected thereto, a carrying shaft for the mast, mounted on a support and having a 40 crank arm, a vertical guide on the support in which said crank arm is freely movable, a drum having a crank, a cable connecting the crank arm and drum, means to prevent retrograde rotation of the drum, and screen 45 supporting means carried by the mast or post and consisting of a main boom mounted for vertical and lateral swinging movement upon the mast or post, and an auxili-

ary or extensible boom mounted for adjustment relative to the main boom, and having 50 said screen connected to the extremity thereof, and means for retaining said parts in their operative relations with the staker spout.

2. A back stop or straw restraining attachment for stackers, having a barrier screen for arrangement in the path of discharge from the stacker spout, a foldable mast or post and means for securing the same in its upright or operative position, a 60 main boom mounted for vertical and lateral swinging movement relative to said mast or post, a sleeve tiltably mounted at an intermediate point of its length upon the outer end of the main boom, an auxiliary 65 boom slidably mounted in said sleeve for extension relative to the main boom and having said screen connected with the forward end thereof, and means for relatively adjusting and securing said elements to 70 maintain the screen in operative relation with the stacker spout.

3. A back stop attachment for a straw stacker, having a mast or post provided with a carrier shaft and means connected 75 therewith for securing the mast in upright position, a main boom mounted upon the mast for vertical and lateral swinging movement, a sleeve pivotally mounted at an intermediate point of its length for tilting 80 movement upon the outer end of the main boom, an auxiliary boom mounted for longitudinal adjustment in said sleeve, a barrier screen adapted for arrangement in the path of discharge from the stacker 85 spout and foldably mounted upon the extremity of said auxiliary boom, means for securing said screen in its operative position with reference to the auxiliary boom, and means for adjusting the angular and 90 longitudinal position of the auxiliary boom with relation to the main boom.

In testimony whereof I affix my signature.

WALTER W. CARSON.
